(57) **CLAIM**

The ornamental design for a bottle, as shown and described.

DESCRIPTION

FIG. 1 is a perspective view of a bottle showing the new design;

FIG. 2 is a front elevational view of the bottle depicted in FIG. 1, the opposite rear elevational view being identical; FIG. 3 is a right side elevational view of the bottle, rotated 90° clockwise; the opposite left side elevational view being identical;

FIG. 4 is a top plan view of the bottle depicted in FIG. 1; and,

FIG. 5 is a bottom plan view of the bottle depicted in FIG. 1.

The broken lines shown in the drawings are for illustrative purposes only and form no part of the claimed design.
